(57) **CLAIM**

The ornamental design for an interlocking outrigger pad support, as shown and described.

DESCRIPTION

FIG. 1 is a top, front perspective view of the interlocking outrigger pad support;

FIG. 2 is another top, front perspective view of the interlocking outrigger pad support;

FIG. 3 is another top, front perspective view of the interlocking outrigger pad support;

FIG. 4 is a bottom, front perspective view of the interlocking outrigger pad support;

FIG. 5 is a top, side perspective view of the interlocking outrigger pad support;

FIG. 6 is a front view of the interlocking outrigger pad support;

FIG. 7 is a back view of the interlocking outrigger pad support;

FIG. 8 is a left view of the interlocking outrigger pad support;

FIG. 9 is a right view of the interlocking outrigger pad support;

FIG. 10 is a top view of the interlocking outrigger pad support; and,

FIG. 11 is a bottom view of the interlocking outrigger pad support.

The broken lines illustrate portions of the interlocking outrigger pad support that form no part of the claimed design.

1 Claim, 11 Drawing Sheets
